CLAIM

The ornamental design for an embankment block, as shown and described.

DESCRIPTION

FIG. 1 is a front perspective view of the embankment block of the subject invention;

FIG. 2 is a top plan view of the embankment block of FIG. 1;

FIG. 3 is a front elevational view of the embankment block of FIG. 1;

FIG. 4 is a side elevational view of the embankment block of FIG. 1, the opposite side being a mirror image thereof;

FIG. 5 is a bottom plan view of the embankment block of FIG. 1; and,

FIG. 6 is a rear elevational view of the embankment block of FIG. 1.

FIG. 1

FIG. 2

FIG. 3

FIG. 4

FIG. 5

FIG. 6
